(21) Appl. No.: **29/416,343**

(57) **CLAIM**
The ornamental design of the food jar with latch-released hinged lid, as shown and described.

(22) Filed: **Mar. 21, 2012**

DESCRIPTION

(51) **LOC (9) CL.** **07-07**

FIG. 1 is a perspective view taken from the upper, rear, right-hand side of the food jar with latch-released hinged lid of the present invention;

(52) **U.S. CL.**

FIG. 2 is a perspective view taken from the lower, front, left-hand side of the food jar with latch-released hinged lid of FIG. 1;

USPC **D7/629; D7/615**

FIG. 3 is a side elevational view of the left side of the food jar with latch-released hinged lid of FIG. 1;

(58) **Field of Classification Search** D7/629,

FIG. 4 is a front elevational view of the food jar with latch-released hinged lid of FIG. 1;

D7/602, 612–615, 608; D9/500, 503, 504,

FIG. 5 is a side elevational view of the right side of the food jar with latch-released hinged lid of FIG. 1;

D9/516, 549, 559, 574, 575; 220/780–806,

FIG. 6 is a rear elevational view of the food jar with latch-released hinged lid of FIG. 1;

220/675, 574–575, 236, 326, 324, 4.23–4.25

FIG. 7 is a top plan view of the food jar with latch-released hinged lid of FIG. 1; and,

See application file for complete search history.

FIG. 8 is a bottom plan view of the food jar with latch-released hinged lid of FIG. 1.
